United States Patent Office

Des. 176,421
Patented Dec. 20, 1955

176,421

STATION WAGON

Clare M. MacKichan, Farmington, Mich., assignor to General Motors Corporation, Detroit, Mich., a corporation of Delaware

Application December 30, 1954, Serial No. 33,761

Term of patent 7 years

(Cl. D14—3)

Fig. 3

Fig. 4

Fig. 1 is a side elevation of a station wagon incorporating my new design;

Fig. 2 is a rear view of the station wagon;

Fig. 3 is a top plan view of the station wagon; and

Fig. 4 is a front view of the station wagon.

The dominant features of my design reside in the full line portion of the drawings.

I claim:

The ornamental design for a station wagon, substantially as shown and described.
